UNITED STATES PATENT OFFICE.

JOHN H. KLENCK, OF WARREN, PENNSYLVANIA.

CAMERA-SUPPORT.

1,156,296.

Specification of Letters Patent.

Patented Oct. 12, 1915.

Application filed August 18, 1914. Serial No. 857,358.

To all whom it may concern:

Be it known that I, JOHN H. KLENCK, citizen of the United States, residing at Warren, in the county of Warren and State 5 of Pennsylvania, have invented certain new and useful Improvements in Camera-Supports, of which the following is a specification.

This invention relates to devices and appliances used for supporting cameras while making the photographic exposure on the sensitized plate or film, and has as its object to supplant the more cumbersome tripod which is usually used for the above mentioned purpose, and also to provide means for supporting a camera from the trunk of a tree, the side of a house, fence, boat, chair-back, or in fact any other suitable and convenient object, and in situations where it 20 might be impossible to use the ordinary tripod.

It is one aim of the invention to provide a support of the class mentioned which may be applied without the use of tools of any 25 sort and readily removed and which will be so constructed that it may be carried in a small space, as for example, in one's pocket.

Another aim of the present invention is to so mount the member of the support, to 30 which member the camera is to be attached, that the camera may be quickly and readily adjusted to the desired position for making the exposure and after having been so adjusted may be securely held in place.

More specifically, the present invention is 35 designed as an improvement on the camera support shown in my copending application, filed June 27, 1914, Serial No. 847,791, and in this connection the invention aims to provide an improved mounting for the clamping 40 device which is arranged to hold the supporting member in adjusted position.

The present invention also aims to provide a shield which may be readily applied 45 to the toothed jaws of the device so that the device may be applied to an article of furniture or the like without liability of marring the finish of the same.

In the accompanying drawings: Figure 1 50 is a perspective view of the device in use. Fig. 2 is a vertical longitudinal sectional view therethrough. Fig. 3 is a horizontal sectional view on the line 3—3 of Fig. 2. Fig. 4 is a perspective view of a portion of 55 one of the jaws and illustrating one of the

shields provided for use in connection with the jaws.

Corresponding and like parts are referred to in the following description and indicated in all the views of the accompanying drawings by the same reference characters.

The device includes a relatively fixed jaw and a movable jaw and the said relatively fixed jaw includes a back 1, an end 2, and sides 3, the end 2 extending between the rear ends of the sides 3 and the said end and the said sides both occupying planes substantially at right angles to the plane of the back 1. The movable jaw includes a back 4 and spaced sides 5. The jaws are pivotally connected by means of a pivot pin 6 which is fitted through the spaced sides 3 and 4 of the said jaws in the manner clearly shown in Figs. 2 and 3 of the drawings, and in order that the jaws may be held yieldably closed, a spring 7 is fitted upon the pin 6 and engages at one end against a lateral lug 8 upon one of the side members 5 of the movable jaw and at its other end against the clamping member for angularly supporting 80 the adjusting element, as will be presently explained. The side members 3 and 5 have their opposing edges of arcuate form and toothed, as indicated respectively at 9 and 10, each series of teeth terminating in a relatively long and sharp pointed tooth 11. In addition to the teeth 9, 10 and 11, the back 1 of the fixed jaw and the back 4 of the movable jaw are formed respectively at 85 their forward ends with transversely positioned teeth 12 and 13. By referring to Fig. 3 of the drawings, it will be observed that the teeth 12 and 13 are spaced apart and are located at opposite sides of the longitudinal middle of the respective jaw so that a space 95 is left between the teeth of each set, as indicated at 14. By referring to Fig. 2, it will be observed that the sides 5 of the movable jaw lie within the sides 6 of the fixed jaw and that the arcuate toothed edges of the 100 said sides 5 and 6 are adapted to coöperate in gripping a fixed object. It will also be understood that the teeth 11 are adapted to coact in this manner as also the teeth 12 and 13, so that the device may be positioned 105 horizontally as shown in Fig. 1 or vertically, in which latter instance, the teeth 12 and 13 become active. In order that the jaws may be pulled apart against the tension of the spring 7, in applying the device 110

to a support, the forward or outer ends of the backs 1 and 4 of the fixed and movable jaws have portions overturned to form pintle lugs 15 pivotally supporting finger rings 16 in which the fingers may be engaged for the purpose stated.

The supporting element of the device comprises a spherical head 17 having a shank 18 projecting therefrom and threaded at its end, as indicated at 19, so as to fit within the tripod socket of a camera or into a similar socket carried by any article, such for example as a mirror, lamp, or the like. The spherical head 17 is fitted within an opening 20 formed in the end 2 of the fixed jaw and this opening is of a diameter slightly less than the diameter of the head, and in order to more or less firmly bind the head 17 against the wall of the opening 20, there is provided a clamping device which comprises a plate 21 having an angularly extending end or clamping head 22 provided with laterally projecting lugs 23 which fit within the notches 24 formed in the edges of the sides 3 of the fixed jaw, the head 22 extending between the said sides and resting against the head 17. A clamping screw 25 having a milled head 26 is fitted rotatably in an opening 27 formed in the back 1 and threaded into an opening in the plate 21 near that end of the plate opposite the end at which the clamping head 22 is located. It will now be apparent that by adjusting the set screw 25, the clamping member may be angularly adjusted upon its lugs 23 as a pivot, and that when the plate or body portion 24 of the clamping member is drawn toward the back 1, the head 22 of the said member will be caused to bear more or less firmly against the head 17 of the supporting element. Of course, when the set screw 25 is loosened, the supporting element may be angularly adjusted to bring the camera to the desired position by rotating its head 17 in the opening 20. By reference to Fig. 2 it will be observed that one end of the spring 7 bears against the head 22 at a point adjacent one of the lugs 23 and that the head therefore serves not only as a clamping means for the supporting element, but also as a stop for one end of the spring.

In order that the device may be applied to an article of furniture without liability of marring the finish thereof, a shield, such as shown in Fig. 4 of the drawings, is provided for the side members of the two jaws, and this shield is preferably formed from resilient sheet metal bent to form spaced sides 28 and a connecting portion 29 having secured thereto in any suitable manner, a facing 30 of rubber or any other suitable material. The connecting portions or backs 29 of the shield are preferably curved to conform substantially to the curvature of the arcuate toothed edges of the said sides

3 and 5, so that when the shield is applied, its sides 28 will frictionally bind against the sides of the respective jaws and the shield will be held against accidental displacement.

From the foregoing description of the invention it will be seen that there is provided an extremely simple device adapted to be readily applied to and removed from any fixed object and adapted, when applied, or so mounted, to support a camera or the like at any desired position of adjustment. It will also be apparent that the clamping member may be applied to a fixed object at practically any desired angle, as for example, in a horizontal position on the side of a post, or in vertical position upon the upper end of the post.

Having thus described the invention, what is claimed as new is:

1. In a device of the class described, pivotally connected jaws, means for closing the jaws, one of said jaws being provided with a bearing portion, a supporting element having a head disposed against the said bearing portion, a member pivotally connected to the said jaw and having a bearing portion located opposite the first mentioned bearing portion and coacting with the head, and means upon the said jaw coöperating with the said member and adjustable to bring the bearing portion of the member into binding engagement with the said head of the supporting element.

2. In a support of the class described, a jaw having a bearing portion provided with a seat, a supporting element having a head fitting within the seat and angularly adjustable, a jaw pivoted to the first-mentioned jaw, a clamping member comprising a body portion and a clamping head, the clamping head being provided with pivot lugs mounted in the sides of the first-mentioned jaw and the said head of the clamping member resting against the head of the supporting element, and means coöperating with the body portion of the clamping member operable to adjust the said member to bring its clamping head more or less firmly into engagement with the head of the supporting element.

3. In a support of the class described, a jaw having a bearing portion provided with a seat, a supporting element having a head fitting within the seat and angularly adjustable, a jaw pivoted to the first-mentioned jaw, a clamping member comprising a body portion and a clamping head, the clamping head being provided with pivot lugs mounted in the sides of the first-mentioned jaw and the said head of the clamping member resting against the head of the supporting element, and means coöperating with the body portion of the clamping member operable to adjust the said member to bring its

clamping head more or less firmly into engagement with the head of the supporting element, the said body portion of the clamping member being located between the said 5 jaws.

4. In a support of the class described, a jaw having spaced side portions and an end portion, the latter being provided with a seat and the side portions being provided 10 in their edges with notches, a clamping member having a head provided with lugs pivotally engaging in the said notches, the head being located opposite the said seat, a jaw pivoted to the first-mentioned jaw, 15 and a supporting element having a head disposed within the said seat and engaged by the head of the clamping member, and means for adjusting the clamping member upon its pivot lugs.
- 20 5. In a support of the class described, a jaw having spaced side portions and an end portion, the latter being provided with a

seat and the side portions being provided in their edges with notches, a clamping member having a head provided with lugs 25 pivotally engaging in the said notches, the head being located opposite the said seat, a jaw pivoted to the first-mentioned jaw, a supporting element having a head disposed within the said seat and engaged by 30 the head of the clamping member, and a set screw carried by the first-mentioned jaw and having threaded engagement with the said clamping member and adjustable to cause the head of the clamping member to 35 more or less firmly bind the head of the supporting element.

In testimony whereof I affix my signature in presence of two witnesses.
